US00D953094S

(12) **United States Design Patent** (10) **Patent No.:** **US D953,094 S**
Chen (45) **Date of Patent:** **** May 31, 2022**

(54) **BARBECUE PAN**

(71) Applicant: **Dongguan HaoHong Outdoor Products Technology Co., Ltd,**
Dongguan (CN)

(72) Inventor: **Jianlin Chen**, Dongguan (CN)

(73) Assignee: **DONGGUAN HAOHONG OUTDOOR PRODUCTS TECHNOLOGY CO., LTD**, Dongguan (CN)

(**) Term: **15 Years**

(21) Appl. No.: **29/762,160**

(22) Filed: **Dec. 15, 2020**

(51) LOC (13) Cl. **07-02**

(52) U.S. Cl. **USPC .....** **D7/363**

(58) **Field of Classification Search**

USPC ..... D7/323, 346, 349, 352, 354, 355, 356, D7/357, 358, 359, 360, 361, 362, 363, D7/364, 365, 366, 367, 402, 409, 550.1, D7/553.2, 553.3, 554.3, 554.4; D10/83, D10/87; D32/53.1, 54, 55 CPC A21B 2/00; A21B 3/00; A21B 3/13; A21B 3/15; A21B 5/00; A21B 5/02; A21B 5/023; A47J 36/02; A47J 36/025; A47J 37/00; A47J 37/04; A47J 37/06; A47J 37/0629; A47J 37/067; A47J 37/10; A47J 47/20; F24C 15/10; F24C 15/102; F24C 15/14; H05B 3/68; H05B 3/681; H05B 3/686; H05B 3/70; H05B 3/72; H05B 6/062
